DEVICE FOR PREVENTION OF FIRES IN OIL STILLS

Filed Oct. 17, 1927

UNITED STATES PATENT OFFICE

ASA F. CORNNER AND GEORGE W. K. KING, OF COFFEYVILLE, KANSAS, ASSIGNEES
OF FIVE-EIGHTHS TO ROY T. OSBORN, OF NEW YORK, N. Y., ONE-FOURTH TO SAID
CORNNER, AND ONE-EIGHTH TO SAID KING

DEVICE FOR PREVENTION OF FIRES IN OIL STILLS

Application filed October 17, 1927. Serial No. 226,788.

Our invention relates to oil stills and particularly to pressure stills, and has for its object, to avoid and prevent fires, and explosions when, for any cause, the pressure in such stills falls below atmospheric pressure. Normally, under working conditions, the pressure in an oil still is more or less above atmospheric pressure, and in the case of pressure stills, the pressure during the running period is many times atmospheric pressure. It sometimes happens, however, due to circumstances into which it is unnecessary to inquire for the present purpose, a still will "puke," that is to say, the liquid contents thereof will be carried over into the condenser, resulting temporarily in a sub-atmospheric pressure in the still. If no precautions were taken to obviate this condition, serious results might ensue from the excess of the pressure of the atmosphere over that in the still. It is, therefore, the common practice to provide such stills with a weighted, inwardly opening valve, so that, before the atmospheric pressure exceeds the internal pressure by a dangerous amount, the valve will open permitting the inflow of atmospheric air into the still to equalize the pressure. But, as the oil and vapors in the still are highly heated, and, in the case of pressure stills, the temperature is much above the ignition temperature, the inflow of air is apt to result in an explosive, combustible mixture in the still and occasion an explosion or a disastrous fire. It is the purpose of the present invention to prevent the occurrence of such fires and explosions by diluting the incoming air with an inert or neutral gas, specifically steam, so that an explosive or inflammable mixture will not be formed. With this object in view we provide means above the safety valve for injecting a neutral gas into the incoming air and connect it to an ample source of steam or other inert gas, controlling the connection by a pressure device responsive to the pressure in the interior of the still so that under normal operating conditions, the steam or other inert gas is shut off, but when the pressure in the still falls below atmospheric and before the pressure differential reaches a point at which it becomes dangerous and the relief valve

opens, the steam or other inert gas will be permitted to flow to the distributing device above the relief valve and discharge above and about the same to mingle with the entering air when the valve opens. 55

In the accompanying drawing we have shown a preferred embodiment of the invention, mainly in vertical section, parts, however, being shown in elevation.

In the drawing, a still to which our invention is applied is indicated at 1. A pipe 2 communicating with the interior of the still leads to a T-union 3. The T is coupled by a short pipe 4 with a valve chamber 5 containing the inwardly opening relief valve 6. 60 The stem 7 of the valve extends upwardly through the valve seat and has a pin and slot connection with the lever 8 from which depends an adjustable weight 9. The lever is pivoted in an opening 10 in a housing 11 65 above the valve chamber and valve seat, said housing being open to the atmosphere at 12.

As above indicated, the relief valve is so counterweighted as to normally remain closed as shown in full lines, but when, by reason of a puke or other abnormal condition, the pressure within the still falls to a point at which the pressure differential between the still and the atmosphere would endanger the still, the valve opens admitting atmospheric 70 air into the still. 75

The housing 11 above mentioned, is cored to form a channel 13, above the valve seat and is perforated as at 14 to form an annular series of holes connecting the channel 13 with the interior of the housing which holes are directed downwardly toward the opening of the valve seat. 85

The side opening of the T³ is connected by pipe 14', and elbow 15, with a piston valve 90 cylinder 16, which in the specific construction shown is arranged with its axis vertical. A piston valve 17 is freely movable in said cylinder, its lower end 18 being exposed to the pressure within the still through the connections mentioned above, and the other end of the piston is formed or provided with a rod 19 extending loosely through an opening 20 in the end wall of the cylinder and formed with an eye 21 outside the cylinder. A coun- 95 100

terweighted lever 22 pivoted at 23 to an ear 24 cast with or mounted on the cylinder engages said eye, said lever being provided with a shiftable counterweight 25.

5 A pipe 26 connected to a suitable source of inert gas or steam, as for example, a boiler, is tapped into the cylinder at one side, as at 27, and immediately opposite the same a pipe 28 is tapped into the cylinder and connected by piping 29 to the steam distributing channel 13 in the housing 11 above mentioned. The piston valve is circumferentially grooved at 30 so that when in the position shown in dotted lines there is free communication between the pipe 26 on the one side leading from the steam boiler and the pipe 28 on the other side leading to the distributing channel 13 of the relief valve housing.

20 In use, the weight 9 is adjusted on the lever 8 to such a position that the relief valve 6 will open only after a sub-atmospheric pressure has been developed in the still and before the pressure differential between the still and atmosphere becomes dangerous. The weight 25 is so adjusted on the lever 22 that the piston valve 17 will normally be maintained in its upper position, shown by full lines, by the pressure of the still vapors 25 on its under face, thus cutting off communication between pipes 26 and 28, but will drop to the dotted line position in which free communication between pipes 26 and 28 is afforded as the pressure in the still falls below atmospheric and before the relief valve 6 opens.

During normal running, therefore, both of these valves remain closed. When the pressure in the still for any cause drops below 40 atmospheric and before it reaches the danger point, first the piston valve and then the relief valve, opens. Just prior to the opening of the relief valve inert gas is discharged above and around the same and when the 45 relief valve opens such gas enters with the air and in such proportion as to avoid the formation of a combustible mixture.

We preferably provide a steam whistle 35 which warns the operator of danger when the piston valve opens.

Furthermore, if desired, an additional pipe 36, connected to the same or some other source of steam or inert gas, may be connected to the channel 13. Preferably, pipe 55 36 is provided with a hand valve for manual control of the flow of steam.

Manifestly, our invention is not confined to the specific structure shown. Other forms of valves, for example, might be used. 60 Instead of the piston valve, a piston or pressure diaphragm connected to a valve of any suitable construction might be used and numerous other changes will suggest themselves to one skilled in the art.

65 We claim:

1. In combination with an oil still, a valve chamber open to the atmosphere, a connection therefrom to the still, a relief valve in said chamber, counter-weighted to remain closed during normal operation and except when the still pressure drops to a predetermined point, connections for supplying inert gas adjacent said valve, a valve in said connections, means counter-weighting the last mentioned valve and a pressure operated device open to the pressure within the still to hold the valve normally closed but to permit it to open at a higher pressure than the first mentioned valve. 70

2. In combination with an oil still, a valve chamber open to the atmosphere, a connection therefrom to the still, a relief valve therein opening toward the still and counter-weighted to remain closed during normal operation and except when the still pressure drops to a predetermined subnormal point, connections for supplying inert gas adjacent said valve, a valve in said connections, a pressure operated device exposed to the still pressure and normally holding the last mentioned valve closed but permitting it to open as the still pressure falls before the first mentioned valve. 80

25 3. In combination with an oil still, a valve chamber open to the atmosphere, a connection therefrom to the still, a relief valve in said chamber, counter-weighted to remain closed during normal operations and except when the still pressure drops to a predetermined sub-atmospheric point, means for distributing an inert gas above the valve, connections for supplying said means with inert gas, a valve in said connections, pressure means influenced by the pressure in the still, normally holding the last mentioned valve in closed position but permitting it to move to open position when the pressure in the still falls below a predetermined point. 95

4. In combination with an oil still, a valve chamber open to the atmosphere, a relief valve in said chamber, a connection from said chamber to the still, a counter-weight for normally holding the valve closed but permitting it to open when the still pressure drops to a predetermined point, connections for supplying steam adjacent said valve, a piston valve in said connections, other connections for exposing said piston valve to the pressure within the still and means for counter-weighting the piston 105 valve. 110

50 In witness whereof, we have subscribed our names.
